The ornamental design for a tire tread, as shown and described.

DESCRIPTION

FIG. 1 is a perspective view of a tire tread of the present application;

FIG. 2 is a perspective view thereof taken from a second side;

FIG. 3 is front view thereof;

FIG. 4 is a side view thereof;

FIG. 5 is a side view of the second side;

FIG. 6 is an enlarged partial perspective view of FIG. 1 (the first side);

FIG. 7 is an enlarged partial perspective view of FIG. 2 (the second side);

FIG. 8 is an enlarged partial front view thereof;

FIG. 9 is an enlarged partial side view of FIG. 4 (the first side); and,

FIG. 10 is an enlarged partial side view of FIG. 5 (the second side).

The region between the inner bead and the sidewall and including the broken line showings that define this region depict subject matter that forms no part of the claimed tire tread design, and is included for the purpose of illustrating the full tire. The tread pattern is understood to repeat throughout the circumference of the tire.
